UNITED STATES PATENT OFFICE.

FRANCIS J. BATCHELDER, OF NEW YORK, N. Y.

APPLIANCE FOR USE IN PLAYING GAMES.

1,176,810.

Specification of Letters Patent.

Patented Mar. 28, 1916.

Application filed December 29, 1915. Serial No. 69,230.

To all whom it may concern:

Be it known that I, FRANCIS JOSEPH BATCHELDER, citizen of the United States, and resident of New York city, in the county 5 of New York and State of New York, have invented certain new and useful Improvements in Appliances for Use in Playing Games, of which the following is a specification.

10 This invention relates to improvements in games, and has for its object to provide an interesting, instructive and at the same time amusing game of skill which will call for the exercise of tactical and strategic capabilities on the parts of the players.

My improved game is played with a board and a number of groups of pieces of different characteristics, the game being playable by any number of players.

20 One of the important features of my improved game lies in the board, which is provided with a number of bases, and paths leading from each base to every other base. Each player is provided with a group of 25 pieces adapted to be moved over the paths above referred to, and the object of each player is to move his pieces along the paths in such a way as to cause the removal of his opponent's pieces from the board; a further 30 object of the players is to be in occupation of the bases of opponents at the close of the game. Additional paths may be provided on the board intersecting those leading from one base to another, thereby materially increasing the sphere of operations, and affording greater opportunity for display of 35 strategic skill on the part of the players. I preferably make these intersecting paths concentric relative to each base, and I provide stations or positions on each path at the

40 points of intersection of these concentric paths with the paths leading from one base to another. The bases may be marked to represent countries or cities, as may be preferred, although this is not essential, and the pieces with which the game is played may represent armies of the opposing countries. In this case the first concentric path around the bases may represent the outlying 45 forts and another path may represent the frontiers of the countries.

The board may be flat, or it may be provided with depressions which form the paths, or the paths may be raised. The 50 playing area may be of any desired out-

line, but in practice I find it preferable to use a circular area.

I will now proceed to describe my invention in detail with reference to the accompanying drawings which shows a board in 60 which the paths are formed on the surface of the board after the manner of a solitaire board.

In the drawings, Figure 1 is a plan view of the board; Fig. 2 is a section taken 65 through same along the line A A of Fig. 1; and Fig. 3 shows one of the pieces which is moved along the board of Figs. 1 and 2.

Referring to the drawings, the board *a* is formed with depressions *b* which form bases 70 as described hereinafter, and each base is connected by paths *c*, *d*, *e* and *f* with every other base. In the example here illustrated five bases *b* are shown, each connected by the aforesaid connecting paths. The series 75 of paths *c* and *f* together form an annulus which defines the boundary of the playing area. Concentric to each of the aforesaid bases are formed paths *g* and *h*, which paths, as shown, intersect the base-connecting paths, *c*, *d*, *e*, and *f*. At the intersections of said paths with the concentric paths *g*, *h*, as well as at the junction of said concentric paths *g*, *h* with the paths *c*, *f*, I provide stations or positions *i*; said stations 80 may be circular or otherwise shaped to position the pieces with which the game is played. An example of one such piece is shown in Fig. 3, said piece consisting of a support *j* for a flag *k*, and while it is preferred to use such a piece, yet it is obvious 85 that any suitable device may be employed for this purpose without departing from my invention.

In using this board to play a military 90 game affording opportunities for a test of skill in strategic movements, each of the movable pieces *j* may represent an army and in the example here shown, each player will have four pieces corresponding with the stations or positions *i* on the arcuate path *g*. The bases *b* are assumed to represent the fortified capitals of various nations and may be inscribed with the names of the capitals of the respective countries. The 95 other positions or stations *i* at the points of intersection of the various paths represent positions which any army may occupy and the paths themselves represent the roads leading to said positions, it being under- 100 105 110

stood that the pieces can be moved only along these roads and from one position to the next.

At the beginning of the game the pieces representing the armies of each nation are placed on the four stations i on the arcuate path g adjacent each base b , it being assumed that the armies are mobilized at these points. Each player in turn, and preferably from right to left, moves any one of his pieces either forward, backward or sideways from one position i to the next, and either to a vacant position or to one occupied by a piece belonging to his opponent. In the latter case, if there is an open position behind the piece of the opponent directly in line with the direction of movement of the piece attacking him, the piece of the opponent is driven back to such open position. However, if there is no open position behind the opponent, in the same path as that in which the attacking piece is situated, the opponent's piece is removed from the board. Should an enemy be forced to move away to a vacant place, he may not reverse his play at his next move and attack the advancing piece, but he may do so at his second move thereafter, if opportunity offers. The movement of some pieces will now be described. Let us assume that the player of the piece marked l wishes to move to the position m which is occupied by the piece n belonging to his opponent. If the position o is unoccupied, the piece l moves to the position m and the piece n is moved up to the position o . However, should this position o be occupied by another piece, the piece n cannot be moved back to position o so that it will be removed from the board counting a loss to the player thereof. The game ends when any player has lost all his pieces, or when any two players have each lost a certain number of pieces, for instance three pieces. The losses are then computed, each piece lost counting "1", and a base occupied by an opponent at the close of the game counting "2", the player with the smallest losses winning. The players may play singly against each other or may play in combination, or a single player may operate a number of groups of pieces each group being played in its right turn. When players join together the scoring is preferably modified to equalize the chances of success.

The losses of the players combined together are preferably added together and then multiplied by the number of groups. Thus when two groups are played against three, the losses of the former are multiplied by two and the losses of the latter by three.

It will be understood that modifications may be made to the rules herein set forth; for instance the paths g may represent fortifications and the paths h may represent the frontiers and any player whose positions on these paths g and h are occupied may be penalized. Other changes may be made in the construction of the board and formation of the pieces without in any way departing from the spirit of my invention as will be apparent to those skilled in the art.

I claim:

1. A game comprising a board, a plurality of bases located on said board in proximity to the exterior of said board, substantially semicircular paths arranged around in front of said bases, and a plurality of paths leading from each base and directly connecting said base with every other base and intersecting said first-mentioned paths.

2. A game comprising a board provided with a plurality of bases, substantially semicircular paths arranged around in front of said bases, a plurality of paths intersecting said first paths and leading from each base and connecting said base with every other base, and a plurality of stations provided at the points of intersection of said paths.

3. A game comprising a board, a plurality of bases located on said board in proximity to the exterior edges of said board, substantially semicircular paths arranged around in front of said bases, and a plurality of paths leading from each base and directly connecting said base with every other base and intersecting said first-mentioned paths in combination with men having distinctive characters corresponding to the bases with which they are associated.

Signed at New York city, in the county of New York and State of New York, this 28th day of December, A. D. 1915.

FRANCIS J. BATCHELDER.

Witness:

HARRY LESSER.
